CONTROLLING MEANS FOR ADJUSTABLE BACK CHAIRS

Oscar A. Reinhold, Flossmoor, Ill.

Application August 28, 1946, Serial No. 693,556

3 Claims. (Cl. 155—163)

1

This invention relates to furniture and is particularly directed to chairs having reclining backs.

In the normal use of a reclining chair, it is desirable to have a soft, gradual moving action when the weight of the user is applied rearwardly against the back of the chair. It is also highly desirable than when the weight of the user is released, that the back of the chair will return in the same easy and gradual manner. It is also desirable for the user to have an easily operated mechanism for adjusting the chair back in various reclining positions.

It is, therefore, the primary object of the present invention to provide a reclining chair of simple and economical construction containing means to achieve an easy positioning action of the chair back, in accordance with the pressure applied or released by the user.

Another object of this invention is to provide a reclining chair in which the user can rigidly secure the movable back at any of several desired positions.

A further object of this invention is to provide a control mechanism for the movable chair back that can be operated by the user with a minimum of effort.

A further object of this invention is to provide a remotely controlled positive latching and de-latching mechanism for a reclining chair.

A further object of my invention is to provide a sturdy operating and latching mechanism which will outlast the normal usage of any chair.

Other objects and advantages of the invention will become apparent from the ensuing description in the course of which reference is had to the accompanying drawings, in which:

Fig. 1 is a side elevational view of the reclining chair with the upholstery removed to more clearly show the operating mechanism. This figure also shows the chair back in phantom lines in two of its reclining positions.

Fig. 2 is a partial perspective view looking at the operating mechanism from the inside of the chair;

Fig. 3 is an enlarged detail illustrating the sliding operating spline for the locking shot-bolt;

Fig. 4 is a sectional view taken on lines 4—4 of Fig. 3, looking in the direction of the arrows;

Fig. 5 is a horizontal sectional view taken generally on lines 5—5 of Fig. 1. This figure also shows the pivotal axle of the movable back.

Fig. 6 is a detailed sectional view of the opposite axle for the movable back;

2

Fig. 7 is a fragmentary internal view looking at the remote control trigger operating mechanism.

Referring to Figs. 1 to 7, inclusive, of the two sheets of drawings, the reclining chair indicated in general by the reference numeral 10, consists of the standard wooden frame construction. The chair has two normal arm rests 12, upright supporting members 14, bottom horizontal frame members 16, and two intermediate horizontal seat supporting members 18.

The intermediate horizontal members 18 are fastened rigidly to the upright supporting members 14 either by doweling or with wood screws as generally used in the art of furniture making. The forward ends of the intermediate supporting members 18 are rigidly secured by wood screws or dowel pins to an upright arm supporting member 20. The two arm assemblies 22 are interconnected by cross tie members 24 and 26. The bottom horizontal members 16 have four short legs 28 at each corner thereof.

Pivotedly supported between the two upright side frame members 14 is a movable back member 30. This movable back member 30 has a horizontal cross member 32 which is interconnected by two downwardly projecting frame members 34. These downwardly projecting frame members 34 are interconnected at its lowermost ends by a cross tie member 36. The movable back member 30 has two rigidly secured axles 38 and 40. These short axles 38 and 40 are riveted at 42 and 44 to two rectangular plates 46 and 48.

The rectangular plate 46 is in turn fastened by machine screws 50 through the downwardly projecting frame member 34 and into the leg portion 52 of the Z-shaped member 54. This Z-shaped member 54 is the mechanical means through which the hydraulic dash-pot 57 transmits its restrictive action to the movable back member 30. Because of the desirability of complete ease of action by the movable back member 30, this snubbing or dash-pot control is more fully disclosed in my co-pending application, Serial No. 648,171, filed February 16, 1946.

The upright supporting members 14 have bushings 56 and 58 to prevent wear in the wooden upright supporting members 14. The rectangular member 48 is fastened to the downward frame member 34 by ordinary wood screws not shown.

The movable back member 30 is held in horizontal alignment by the retaining rings 60 and 62. The retaining ring 60 is pinned to the axle 38 by pin 64. This prevents any movement to the right, as can readily be seen. The rigid axle

on the other side is prevented from movement to the left by a retaining washer 84 and screw 86. Any thrust delivered to the left is taken up by the flanged bushing 58 and anti-friction washer 88. The retaining ring 80 on the left side is held between two fixed plates 78 and 12, which plates act as additional thrust members for the retaining ring 80.

The fixed plate members 78 and 12 act as a housing assembly 14 for the latching mechanism 16. The advantage of this two plate housing assembly 14 is to provide a complete unitary mounting for the latching mechanism 16. The housing assembly 14 is mounted by wood screws 78 to the upright supporting member 14 and by the wood screw 80 to the intermediate seat supporting member 18.

Fixed plate member 78 has a multiplicity of arcuately spaced holes 82 through which shot-bolt 84 engages and retains the movable back member 30 in any of the several reclining positions. The shot-bolt 84 has a plurality of annular equally spaced teeth 86. The teeth 86 are constantly in engagement with a long splined member 88 which is fixedly attached to an actuating rod 90. When the user of the reclining chair wishes to change his angle of repose, he merely pushes downwardly on the trigger 92, which causes the actuating rod 90 to rotate in its bearing 94, thereby rotating splined member 88 which in turn withdraws shot-bolt 84 from the spaced holes 82 against the force of compression spring 96.

The shot-bolt assembly is housed in a pivotal casting 98. Pivotal casting 98 is held in horizontal alignment between one arm of the Z-shaped member 54 and a U-shaped member 100. The reason for the pivotal action of the casting 98 is to keep the splined member 88 tangential to the annular spaced teeth 86. No matter what position the actuating rod 90 and splined member 88 assume in relationship to their movement, the trigger 92 is always approximately in the same position for the user's manipulation.

If the user maintains constant pressure downwardly on trigger 92, the movable back member 30 can be moved forwardly or rearwardly to any desired position. If the user merely presses trigger 92 downwardly for an instant, the movable back member 30 will either move forward or backward to the next spaced hole 82, as the user desires. When shot-bolt 84 is withdrawn from spaced holes 82 and the user releases the trigger instantly, the shot-bolt nose rides on the inner face of fixed plate member 78 under spring pressure 96. Then as the shot-bolt comes in register with the next spaced hole 82, compression spring 96 forces the shot-bolt 84 into register with the next spaced hole 86.

The forward end of the outer leg 102 on the Z-shaped member 54 has a tensioning member 104 attached thereto. This tensioning member 104 can be adjusted to a predetermined pull and then permanently locked by nuts 106. Lock nuts 106 bear against a mounting plate 108, said mounting plate 108 being attached rigidly to the horizontal bottom members 16. The end portion of the outer leg 102 has thereto mounted a bifurcated yoke 110 which is one of the mounting ends of the dash-pots 57. The other end of dash-pots 57 are pivotally mounted to a trunnion 112 fixedly secured by bolts or other means to the bottom horizontal member 16.

It will be understood that there are two sets of Z-shaped members 54, two dash-pot members

57 and tensioning members 104 located in the two arm assemblies 22, although only one is shown by the illustration in Fig. 1. This is necessary to assure a smooth and balanced operation of movable back member 30. However, it is obvious that only one latching mechanism 16 is necessary.

In conclusion, although my invention has been disclosed in connection with the specific details of preferred embodiments thereof, it must be understood that such details are not intended to be limitative of the invention except in so far as set forth in the accompanying claims.

I claim:

1. A chair having in combination, a supporting body structure, a back pivotally attached thereto, said movable back member having a dash-pot and a return tensioning member affixed thereto, the lower ends of the dash-pot and return tensioning member being secured to the supporting body structure, the supporting body structure having a fluted control member pivoted to the back and engaging the latching means for moving the latter into operative and inoperative position, a fluted pivoted control member for engaging and disengaging the said latching means, the fluted pivoted control member having an extension arm supported on a bearing support means on said body structure.

2. A chair having in combination, a supporting body structure, a back pivotally attached thereto, said movable back member having a dash-pot and a return tensioning member affixed thereto, the lower ends of the dash-pot and return tensioning member being secured to the supporting body structure, the supporting body structure having a fluted control member pivoted to the back and engaging the latching means for moving the latter into operative and inoperative position, a fluted pivoted control member for engaging and disengaging the said latching means, said fluted pivoted control member positively engaging a shot-bolt and the pivotal connection of the control member to the back permitting the control member to slide in the plane 35 angular to the horizontal plane of said shot-bolt, the shot-bolt passing through an arm member fixedly secured to said pivotal back member, the shot-bolt engaging or disengaging a fixed latching plate mounted on said supporting structure, 50 the fluted pivoted control member having an extension arm pivotally supported on a bearing support means on said body structure.

3. A chair having in combination, a supporting body structure, a back pivotally attached thereto, said movable back member having a dash-pot and a return tensioning member affixed thereto, the lower ends of the dash-pot and return tensioning member being secured to the supporting body structure, the supporting body structure having a fluted control member pivoted to the back and engaging the latching means for moving the latter into operative and inoperative position, a fluted pivoted control member for engaging and disengaging the said latching means, 55 said fluted pivoted control member positively engaging a shot-bolt and the pivotal connection of the control member to the back permitting the control member to slide in the plane angular to the horizontal plane of said shot-bolt, the shot-bolt passing through an arm member fixedly secured to said pivotal back member, the shot-bolt engaging or disengaging a fixed latching plate mounted on said supporting structure, said shot-bolt having a resilient forcing member to urged the shot-bolt into register with said latch-

ing plate, the fluted control member having an extension arm pivotally supported on a bearing support means on said body structure.

OSCAR A. REINHOLD.
